UNITED STATES PATENT OFFICE

158,195

TRANSCEIVER CABINET PANEL

Harry K. Hudson, Garden City, N. Y., assignor
to The Sperry Corporation, a corporation of
Delaware

Application October 8, 1947, Serial No. 141,809

Term of patent 7 years

(Cl. D26—5)

To all whom it may concern:

Be it known that I, Harry K. Hudson, a citizen of the United States, residing at Garden City, in the county of Nassau and State of New York, have invented a new, original, and ornamental Design for Transceiver Cabinet Panels, of which the following is a specification, reference being had to the accompanying drawing, forming part thereof.

In the drawing:

Fig. 1 is a front elevational view of a transceiver cabinet panel showing my new design;
Fig. 2 is a plan view thereof;
Fig. 3 is an end view of my design; and
Fig. 4 is a perspective view thereof.

I claim:

The ornamental design for a transceiver cabinet panel, as shown.

HARRY K. HUDSON.
